SINKER HEAD

Stanley Gagas, Perkasie, Pa.

Application February 16, 1945, Serial No. 578,189

3 Claims. (Cl. 66—110)

1

This invention relates to a sinker head, and more particularly to such a sinker head adapted to be utilized in conjunction with knitting machines adapted for the fashioning of full-fashioned hosiery.

A primary object of this invention is the provision of an improved sinker head, characterized by a plurality of removable spacers, in order that in the event of any damage to a portion of the head, that portion may be replaced without the necessity of replacing the whole unit.

An additional object of the invention is the provision of such a sinker head which may be constructed of any desired material, the intermediate portion being constructed of any suitable metal, plastic, or if desired, any other suitable substance.

A still further object of the invention is the provision of a sinker head so designed and constructed that the gage of the machine with which it is utilized can be changed by removal of certain associated parts thereof and replacement of these parts with others of a desired gage.

A still further object is the provision of such a sinker head which will be sturdy and durable in construction, reliable and efficient in operation, and relatively simple and inexpensive to manufacture, assemble, and utilize.

Other objects will in part be obvious and in part be pointed out as the description of the invention proceeds and shown in the accompanying drawings, wherein there is disclosed a preferred embodiment of this inventive concept.

In the drawings:

Figure 1 is a front elevational view of a sinker head constructed in accordance with the instant invention.

Figure 2 is a top plan view of the sinker head as disclosed in Figure 1.

Figure 3 is an end elevational view of the device shown in Figures 1 and 2.

Figure 4 is an end elevational view showing portions of the sinker head in association with certain additional mechanism.

Figure 5 is a sectional view taken substantially along the line 5—5 of Figure 4, certain parts thereof being shown in elevation.

Figure 6 is a perspective view of one of the spacer plates comprising a feature of the instant invention.

Similar reference characters refer to similar parts throughout the several views of the drawings.

Having reference now to the instant invention, the device is comprised of a pair of oppositely

2

disposed sinker head brackets or end plates 10, each of which is preferably machined from a single piece of metal or the like, between which extend two spacer rods 11 and 12, each adapted to be held in position as by means of nuts 13 and 14, respectively. Between the end plates 10 are positioned a plurality of spacer plates or spacers 15, each as best shown in Figure 6 provided with apertures 16 and 17 through which rods 11 and 12, respectively, are adapted to pass, and each provided with a horizontally extending transverse slot 18, adapted to permit the passage therethrough of a sinker 19 or divider 20 (see Figure 4). As best shown in Figure 6 the spacer plates 15 are provided with horizontal channels or grooves 19 to permit entry of the reinforcing portion 21 of the sinker. When the device is in assembled relation, it will thus be seen that the number of plates 15 may be readily varied as desired to provide a sinker head of any desired length or gage, it will also be seen that various types of spacers having slots or grooves 19 of various sizes may be provided as desired for the particular machine with which the device is used.

As best shown in Figure 4, the sinkers 19 are alternately positioned between dividers 20 adapted to be engaged by a catch bar 21. The device is adapted to be utilized in the conventional manner in a full fashioned hosiery knitting

30 machine.

Means for aligning the spacers accurately are also provided, such means taking the form of suitable morticed grooves 23 aligned along the upper face of all the spacer plates 15, and extending into the end plates 10, through which is passed a tenoned bar 24 of steel or the like, serving effectively to hold the parts in aligned related assembly.

From the foregoing it will now be seen that the 40 sinker head of the instant invention comprises a unitary structure which serves to supplant previously constructed sinker heads comprised of top and bottom plates, formed as an integral unit, which required replacement should any portion thereof become damaged. It will also be seen that by means of the instant invention in the event that any portion of the device becomes damaged, such as illustratively one of the plates 15 the same may be readily replaced with a minimum of difficulty and effort. It will correspondingly be seen that the gage of the machine may be readily varied by replacing the spacers 15 by different gage spacers.

It will also be seen that there is herein provided a device accomplishing all the objects of

the instant invention and many others including advantages of great practical utility and commercial importance.

As many embodiments may be made of this inventive concept, and as many modifications may be made in the embodiment hereinbefore shown and described, it is to be understood that all matter herein is to be interpreted merely as illustrative and not in a limiting sense.

I claim:

1. In a sinker head, in combination, a pair of end plates, rods extending between said end plates, and a plurality of divider and sinker supporting spacers mounted on said rods positioned between said end plates, each of said spacers being horizontally grooved to provide a transverse passage for said dividers and sinkers, and an aligning bar morticed in the upper edges of said spacers.
2. In a sinker head, in combination, a pair of 20

end plates, rods extending between said end plates, and a plurality of divider and sinker supporting spacers mounted on said rods positioned between said end plates, the extremities of said rods being threaded, nuts on said extremities to hold the plates in related assembly, and an aligning bar having locking shoulders adapted to interlock with correspondingly shaped grooves in said spacers for aligning the same.

- 10 3. In a sinker head, in combination, a pair of end plates, rods extending between said end plates, a plurality of divider and sinker supporting spacers mounted on said rods positioned between said end plates, means forming morticed grooves in the upper edges of said plates and spacers, and an alignment bar having cooperating morticed opposite sides positioned in said grooves.

STANLEY GAGAS.
